UNITED STATES PATENT OFFICE.

PATRICK F. O'LEARY, OF CLEVELAND, OHIO.

RUBBER HEEL.

Application filed May 8, 1922. Serial No. 559,367.

To all whom it may concern:

Be it known that I, PATRICK F. O'LEARY, a citizen of the United States, residing at Cleveland, in the county of Cuyahoga and 5 State of Ohio, have invented certain new and useful Improvements in a Rubber Heel, of which the following is a specification.

This invention consists of a rubber heel having a resilient shank portion which is 10 particularly constructed and arranged to cushion in a predetermined degree a definite localized area in the arch of the foot, and which shank portion is extended at an inclination to the base of the heel to promote 15 a gradual uplift of the arch and a comfortable walking action, especially to persons having fallen or weak arches.

In the accompanying drawing, Fig. 1 is a side view of a shoe provided with a heel 20 of my improved construction. Fig. 2 is a bottom view of the shoe and heel shown in Fig. 1. Fig. 3 is a plan view, enlarged, of the heel itself, and Fig. 4 is a sectional view on line 4—4 of Fig. 3. Fig. 5 is an edge 25 elevation of the breast side of the heel.

The dotted lines in Fig. 1 represents the skeleton or frame work of a human foot, and show numerous but not all of the joints or articulations or the twenty-six bones 30 therein. The relative position of the bones as shown indicate a weak arch as occurs when the ligaments become strained or stretched and lose their tone. Under these conditions the heel tires and becomes tender, 35 the ankle tends to turn suddenly, pains occur, constant standing or walking causes general discomfort, and a broken down arch and flat foot develop. Under pressure and weight the foot also elongates as the inner 40 longitudinal or long arch of the bone structure flattens, causing discomfort to the toes. In a weak foot the natural balance of the foot is also interfered with, imposing additional strains on various parts of the foot.

To relieve and remedy such weakened foot 45 conditions and bring about a more normal functioning in a weak foot, I have designed a rubber heel in which the main body 2 is rounded at its rear and opposite sides and 50 of irregular outline at its front side where a relatively narrow and short extension 3 is formed integrally with the body on the longitudinal medial line thereof. This heel is fastened to the shoe by means of nails driven through body 2, but the small pad or 55 extension 3 is not nailed to the shoe except

at its base or juncture with body 2. Instead, said extension is molded to curve or slant upwardly and forwardly in respect to the flat bottom 4 and the concaved top 5 of the heel so that it will be placed under constant compression and fit snugly at all times against the bottom shank portion 6 of the sole of the shoe S when the body of the heel is nailed thereto. To further effect 60 a snug and tight union at the meeting faces of the shoe bottom and the pad or extension 3 a small shallow cavity 7 is formed within the upper face of the extension, thus providing a narrow border seat 8 of tapering 65 cross section adapted to be readily compressed in making a tight joint. A central round protuberance 9 within cavity 7 also engages the bottom of shank portion 6 when the heel is in place on the shoe, and the extension 3 is thus made quite resilient and 70 functions as a cushioning pad centrally of the instep immediately beneath the astragalus bone 10 and in line with the tibia 11 substantially opposite the joint 12 between 75 the scaphoid 13 and the os calcis or heel bone 14 where the long and short plantar ligaments span and give support to the arch of the foot.

The os calcis and scaphoid bones are 80 joined together with another bone called the cuboid which is laterally opposite the scaphoid but not shown, the meeting point being substantially on the medial line of the foot directly above the cushioning pad or 85 extension 3 which is designed to exert a resilient uplifting effect at this spot in standing or when walking. In other words the pressure upon the foot is localized within a given area opposite the articulations 90 immediately in line with the bones in the leg which carry the weight down into the foot and the extension is narrow and relatively short or of a definite length for that reason. The extension is inclined or also made slanting 95 in respect to the flat bottom of the rubber heel to further localize the pressure and weight to this central spot or place in the foot whether the wearer is standing or walking.

The normal foot has three bearing points, two in front and the heel bone 14 at the rear. The load is carried between these points and the articulations permit the arch to flatten subject to the natural limitations 100 of the muscles and ligaments. With the present invention a weak foot is materially 110

aided in supporting the weight where a support is most needed but without harsh resistance or solid impact extended over a large area. Thus, in standing the weight is distributed over the entire foot with a slight uplift and additional pressure in the small local area of the pad or extension 3, this action being clearly shown in Fig. 1 by the arrow *a* pointing upwardly, and the arrow *b* pointing downwardly, it being further understood that this view is of a shoe before it is flexed by the weight therein. Placing weight on the foot depresses the heel bone 14 and the body 2 of the heel but in the meantime the arch of the foot is obtaining the aid of the middle pad or cushioning extension 3. In walking a slightly different action occurs because the rear end of the heel usually strikes first and then the sole of the shoe before flattening the arch. With my improved heel the rear end strikes first and flattens, then the shank flexes as the pad or cushioning extension 3 strikes and compresses and becomes the fulcrum for distributing the weight to the sole as it strikes the ground, the ligaments of the foot being resiliently aided by the pad 3 in sustaining the arch of the foot in this movement. The body of the heel may also be provided with a recess 15 within its upper side to promote resiliency beneath the heel bone 14, and where such a recess is provided in connection with a narrow pad or extension 3 the bridge portion or transverse area 16 intermediate recess 15 and the cavity 7 is made more resilient and co-acts with the extension in localizing the pressure in and beneath the shank of the shoe.

The heel and its extension being spaced 40 apart and not connected with the sole beneath the ball of the shoe the wearer may double up and bend the foot freely as in an ordinary shoe. The shank may also be flexed freely between extension 3 and the sole of the shoe, and this space being open and unobstructed the heel can function as an ordinary heel in walking up inclines, gang planks, in climbing ladders, etc. 45

What I claim, is:

1. A shoe having a curved shank and a rubber heel, said heel having a relatively short and narrow integral extension slanting upwardly from the breast of the heel and on the longitudinal medial line thereof, said extension providing a short cushioning pad in a small localized area beneath the shank of the shoe. 50

2. A rubber heel for a shoe, having a short integral extension of substantially the same thickness as the main body of the heel and extending upwardly at an inclination from the middle of the breast of the heel, both the top and bottom surfaces of the extension slanting upwardly from the breast. 55

3. A rubber heel for a shoe, having a concaved upper face and a flat bottom and formed with a short narrow integral extension extending upwardly at a slight inclination from the breast of the heel, the top of said extension being cupped and the bottom being flat, the length of said extension being approximately the same as the width thereof. 60

In testimony whereof I affix my signature. 70

PATRICK F. O'LEARY.
